(57) **CLAIM**

The ornamental design for a shower accessory container, as shown and described.

DESCRIPTION

FIG. 1 is a front isometric view of a shower accessory container showing my new design;

FIG. 2 is a rear isometric front view thereof;

FIG. 3 is a front elevation view thereof;

FIG. 4 is a rear elevation view thereof;

FIG. 5 is a right side elevation view thereof;

FIG. 6 is a left side elevation view thereof;

FIG. 7 is a bottom plan view thereof;

FIG. 8 is a top plan view thereof; and,

FIG. 9 is an exploded view thereof.

The broken lines show portions of the design that form no part of the claimed design.
